(57) **CLAIM**

The ornamental design for a video camera, as shown and described.

DESCRIPTION

The patent or application file contains at least one drawing executed in color. Copies of this patent or patent application publication with color drawing(s) will be provided by the Office upon request and payment of the necessary fee. FIG. 1 is a front perspective view of a video camera showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top side view thereof; and,

FIG. 7 is an enlarged bottom side view thereof.

The broken lines and areas within them in the drawings depict portions of the video camera that form no part of the claimed design.

1 Claim, 7 Drawing Sheets
